UNITED STATES PATENT OFFICE.

JOHN W. RAPP, OF FLUSHING, AND JOSEPH VANORIO, OF BROOKLYN, NEW YORK; SAID VANORIO ASSIGNOR TO SAID RAPP.

KNOCKDOWN CONSTRUCTION FOR AIRPLANE-WINGS AND THE LIKE.

1,325,499.

Specification of Letters Patent. Patented Dec. 16, 1919.

Application filed January 19, 1918. Serial No. 212,784.

To all whom it may concern:

Be it known that we, JOHN W. RAPP and JOSEPH VANORIO, citizens of the United States, and residents, respectively, of Flushing, Queens county, New York, and Brooklyn, in the county of Kings and State of New York, have invented certain new and useful Knockdown Constructions for Airplane-Wings and the like, of which the following is a specification.

This invention relates to improvements in knock-down constructions for airplane wings and the like.

The primary object of this invention is to produce a construction of airplane wing or the like which may be readily and quickly knocked down and reassembled and which when so reassembled will have all the strength and rigidity of a wing which is permanently erected initially, and said invention consists essentially of the provision of substantially parallel frame or cross members in combination with a series of rib units each of which is provided with means adapted to slide over or on said frame or cross members, means for spacing such units from each other and means for firmly fastening such units and frame members together.

In a more intense aspect, our invention comprises the provision in a wing frame of parallel marginal frame members and intermediate spars, rib units having ferrules at opposite ends adapted to slidely fit over said marginal frame members, spacing pieces at the front and rear also adapted to slide over each of said marginal frame members and to abut against adjacent rib ferrules said spacing pieces at the front preferably carrying filler strips adapted to extend inwardly and to be connected with a spar extending through said rib units.

In the accompanying drawings, in which similar reference characters designate corresponding parts throughout the several views,

Figure 1 is a plan view of an airplane wing embodying our invention;

Fig. 2 is a similar view showing the parallel cross members connected to a curved end piece with two rib units and spacing pieces slid over the marginal parallel frame members and the spars;

Fig. 3 is a side elevation of a rib unit of relatively heavy construction and preferably

employed in combination with the spars to form the tension frames of said wing;

Fig. 4 is a plan view of the rib shown in Fig. 3;

Fig. 5 is a plan view of a relatively light form of rib unit employed intermediate the heavy rib units of the tension frames;

Fig. 6 is a plan view of the rib unit shown in Fig. 5;

Fig. 7 is a plan view of the spacing ferrule employed by me which carries the filler strips adapted to bridge the space between the marginal frame member and the spar at the front of the wing;

Fig. 8 is a side elevation of the ferrule and filler strips shown in Fig. 7;

Fig. 9 is a plan view showing the strut block and the connecting straps for the tension wires;

Fig. 10 is a side elevation of the block shown in Fig. 9; showing the spar in section;

Fig. 11 is a plan view of a corner showing the connection between the front spar and a heavy rib unit; and

Fig. 12 is a side view of the rib unit, showing the spar in section.

Referring now to these drawings, 1 indicates an end piece of a wing to which is securely fastened by screw-threads or other suitable detachable means, two parallel marginal frame members 2 and 3 respectively which as shown are in the form of round pipes of less circumference than the pipe of which the marginal portions of the end member is formed, and 5 and 6 are respectively front and rear spars which are likewise suitably fastened in a detachable manner to the end piece or rib 1. In accordance with this invention, each of the rib units except the end piece or rib is provided with ferrules 7, 7^a or the like at opposite ends which are adapted to be slid over the round pipe sections of the marginal frame. Certain of said units also have intermediate the ends thereof strut blocks or other fastening means in accordance with the position to be occupied by the particular rib in the wing construction. As illustrated, each rib carries perforated lugs 8, 8^a and 9, 9^a for connection to the respective spars, and these perforated lugs register with apertures in the spars to permit the passage through the spar apertures and such lugs of a bolt, rivet or the like when the wing construction is set

up permanently. 10 indicates rear spacing ferrules adapted to slide over the rear marginal frame member and to separate or space the individual ribs from each other at the 5 rear and 10^a indicates front spacing ferrules of similar length to the ferrules 10 which are slid over the front marginal frame member and separate the adjacent ferrules of the rib units from each other at this end. This 10 ferrule 10^a preferably carries filler strips 11 which span the distance between the front marginal member and the first spar.

In Figs. 9 and 10, I have shown a strut block 15 comprising top and bottom plates 15 16 and 17 connected by posts 18 which, as shown, are suitably connected as by welding to the rib portions on opposite sides thereof and has an opening to permit the spar beam 6 to extend therethrough between its posts.

20 It will be obvious that when it is desired to erect a wing of our construction, it will only be necessary, after connecting the marginal frame members and the spars to the end piece or rib as above described to slide 25 on a spacing ferrule at the rear and another at the front, then slide on a rib unit in accordance with its proper position in the completed wing, and then to slide over the said frame members additional spacing 30 pieces and rib units, after which a suitable rib unit 12 which preferably carries integral pivot-knuckles 13 for connection to the fuselage of the machine at the opposite end is put into place. The various ribs and ferrules 35 may then be tightened up by nuts 14 and may be connected to the spars in any suitable well-known manner. After a wing is so assembled, or during the process of assembly the tension wires may of course be 40 connected up and suitably tensioned.

A wing assembled in this way will have all the rigidity and strength and will be in all respects equal to a wing which is permanently put together in the first instance.

Having described our invention, we claim: 45

1. A knock-down wing construction for airplanes embodying parallel marginal frame members, rib units having ferrules at opposite ends of the same conformation as said frame members and adapted to slid- 50 ily fit over said frame members, means for spacing said rib ferrules and means for securing the ribs, spacing means and frame-members together.

2. A knock-down wing construction for 55 airplanes embodying parallel frame members at opposite ends of the wing, rib units having ferrules at opposite ends of the same conformation as said frame members and adapted to slidily fit over said frame mem- 60 bers and spacing ferrules at the opposite ends also adapted to slidily fit over said frame members and to abut between adjacent rib ferrules, and means for securing the ribs, spacing ferrules and frame-members to- 65 gether.

3. A knock-down wing construction for 70 airplanes embodying parallel frame members at opposite ends of the wing, rib units having ferrules at opposite ends of the same conformation as said frame members and adapted to slidily fit over said frame members and spacing ferrules at the opposite ends also adapted to slidily fit over said 75 frame members and to abut between adjacent rib ferrules, filler strips carried by said spacing ferrules and means for securing the ribs, spacing ferrules and frame-members together.

Signed at College Point, in the county of 80 Queens and State of New York this 8th day of January A. D. 1918.

JOHN W. RAPP.
JOSEPH VANORIO.
